UNITED STATES PATENT OFFICE.

IRA CULVER, OF CLEVELAND, OHIO.

VAPOR-BURNER.

SPECIFICATION forming part of Letters Patent No. 499,969, dated June 20, 1893.

Application filed June 29, 1892, Serial No. 438,431. (No model.)

To all whom it may concern:

Be it known that I, IRA CULVER, of Cleveland, in the county of Cuyahoga and State of Ohio, have invented certain new and useful 5 Improvements in Vapor-Burners; and I do hereby declare the following to be a full, clear, and exact description of the invention, such as will enable others skilled in the art to which it pertains to make and use it, reference being 10 had to the accompanying drawings, which form part of this specification.

My invention relates to an improvement in vapor burners; and it consists in the novel features of construction, and in the combination 15 and arrangement of parts which will be fully described hereinafter, and more particularly referred to in the claims.

The object of my invention is to construct a new and improved burner which will most 20 thoroughly vaporize the hydrocarbon, and which will also procure from the vapor the maximum amount of heat.

Referring to the accompanying drawings,— Figure 1, is a vertical sectional view of my 25 improved burner. Fig. 2, is a plan view of the base of the same. Fig. 3, is a horizontal sectional view on the line 3—3 of Fig. 1. Fig. 4, is a plan view of the burner, the cap being 30 removed. Fig. 5, is a similar view of the distributing cap.

The base of the burner consists of a series of troughs or passages A, which radiate from a common center and which are all connected or in communication at this point. This portion 35 is preferably formed of a single casting which is slightly raised at its center and this raised portion is constructed with a vertical passage which communicates with the overflow chamber B, presently to be described.

40 Projecting vertically from the respective sides of the troughs or passages A, are the perforated sides or partitions C. The adjacent sides C, of the respective troughs are connected at their upper ends by the webs D, 45 of the casting E, so that while the spaces between the troughs are covered at the upper end of the burner continuous upward passages exist directly over the troughs. The perforated partitions as well as the base of the 50 burner are inclosed in the outer casing F.

Depending from the center of the casting E, is the tube or chamber G, closed at both

ends as shown and to the exterior of this chamber the inner edges of the partitions C, are secured.

55

H, represents downwardly bent tubes or passages projecting from the lower end of the chamber G, which project downward over the respective troughs A.

Extending into and communicating with 60 the chamber G, is the pipe I, which is reduced in size at the point of connection as shown. This pipe extends toward the burner at a downward incline and secured to its outer end is the joint J, having the two horizontal openings K, L, and the vertical inlet M. To the opening K, is connected the pipe leading to the elevated tank N. In the vertical opening M, is adapted to move the needle valve O, which is operated by a hand wheel O', in the 65 usual manner.

Secured to and extending from the stem of the valve is the arm P, which is adjustable thereon as shown.

Projecting upward from the joint J, is the 75 stop Q, against which the arm P, strikes thus stopping the movement of the valve. By adjusting the said arm on the valve stem it will be seen that the amount of oil admitted to the burner from the tank can be regulated with 80 great accuracy as the valve owing to the above described construction will be allowed to open only a predetermined distance. One of the troughs A, is extended as shown at R, and this extended portion is covered by the weight- 85 ed lid S. By this construction a convenient lighting or igniting point is provided. As the troughs are all in communication at their inner ends the flame will spread from one to the other until all are lighted, although the fire 90 is first applied to only one.

Placed upon the upper end of the burner is the deflector plate T, for the purpose of spreading the flame. This plate consists of a circular piece of metal having two or more concentric series of bulges or dips U, which are pushed upward as shown, their inner uncut ends forming their supports. By this construction it will be seen that the flames and heat therefrom will be most effectually spread 100 and distributed evenly to the under surface of the object being heated.

In operation when it is desired to start the burner, a small quantity of fluid is allowed to

pass the valve K, which entering the chamber G, continues its passage to the troughs A, into which it is evenly distributed. This fluid is then ignited at the extension R, and the 5 flames rising around the chamber G, between the perforated partitions C, soon heat the former so that when more fluid is passed thereto it will be vaporized which descending feeds the flames at the burning points in the 10 troughs A. The flames feed upward between the respective inclosing partitions C, an abundance of air being supplied them through the perforations from the spaces between the respective trough sections. The inlet to the 15 overflow chamber B, being slightly raised a small depth is given to the troughs but if from any cause the fluid is fed too rapidly the troughs will overflow and the surplus will run into the said chamber from which it will 20 gradually vaporize and pass upward to the flame. Thus a safe guard is provided there being no danger of the burner overflowing. The overflow chamber is cylindrical being screw threaded at its upper end where it attaches to the central screw threaded opening in the trough casting as shown. By this construction a simple yet powerful burner is provided.

Having thus described my invention, I 30 claim—

1. A burner comprising a central vaporizing chamber, a series of communicating troughs radiating from beneath the center thereof, the chamber and troughs being in communication, a liquid supply leading to the said chamber, perforated partitions projecting vertically from the respective sides of the troughs, and an outer casing; substantially as shown and described.

2. A vapor burner comprising a central vaporizing chamber, radiating and communicating troughs beneath the chamber which also communicate with the chamber, a liquid supply in connection with the chamber, perforated partitions projecting vertically from the sides of the troughs, suitable covers at the upper end of the burner for the spaces between the adjacent partitions of the adjacent burners, and an outer casing substantially as shown and described.

3. A vapor burner comprising a central vaporizing chamber, radiating and communicating troughs beneath and in communication with the chamber, a liquid supply in connection with the chamber, perforated partitions projecting vertically from the trough sides, a webbed casting on the upper end of said chamber and covering the spaces between the adjacent sides of the adjacent troughs, a deflector above said casting, and an outer casing, substantially as shown and described.

4. A vapor burner comprising a central vaporizing chamber, an oil supply into said chamber, a series of radiating and communicating troughs beneath and in communication with the said chamber, and an overflow

reservoir depending from the inner connected ends of troughs, substantially as shown and described.

5. A vapor burner comprising a central vaporizing chamber, a series of radiating and communicating troughs directly beneath the said chamber which are formed of a single casting and which are in communication with said chamber, an upward bulge in the center of the said casting having a vertical passage, and a depending overflow chamber connected to said passage, substantially as shown and described.

6. A vapor burner comprising a central vaporizing chamber into which the oil is fed, a series of radiating troughs beneath said chamber and closed at their outer ends, said chamber communicating with each trough, a casing surrounding the outer ends of the troughs, one trough being extended beyond said casing and provided with a lid, substantially as shown and described.

7. A vapor burner comprising a central vaporizing chamber, a liquid supply in communication therewith, a series of radiating and communicating troughs beneath and in communication with the lower end of the said chamber, vertical perforated partitions projecting from the sides of the troughs, covers for the upper ends of the spaces between the adjacent partitions of the adjacent sides, an outer inclosing case, an upward vertically perforated bulge at the radiating point of the troughs, an overflow chamber connected thereto, one of the said troughs being projected beyond the said inclosing casing, and a cover for the extended portion, substantially as shown and described.

8. A hydrocarbon burner comprising a central vertical vaporizing chamber, an oil supply thereto, a series of burner chambers arranged around and radiating from said central vaporizing chamber, and outlets from said vaporizing chamber into said burner chambers, substantially as specified.

9. A hydrocarbon burner comprising a central vertical chamber, an oil supply thereto, a series of burner chambers arranged around and radiating from and communicating with said central chamber, and closed except at the top, said burner chambers separated by vertical perforated partitions, substantially as set forth.

10. A burner having a central vertical chamber, an oil supply thereto, a series of burner chambers arranged around and communicating with and radiating from said central chamber, and having their bottoms located below the lower end of said central chamber, substantially as shown and described.

In testimony whereof I affix my signature in presence of two witnesses.

IRA CULVER.
